(57) **CLAIM**

The ornamental design for the knife handle, as shown and described.

DESCRIPTION

FIG. 1 is a perspective view of design for a knife handle according to one embodiment;

FIG. 2 is a right side view of the knife handle shown in FIG. 1;

FIG. 3 is a left side view of the knife handle shown in FIG. 1;

FIG. 4 is a top plan view of the knife handle shown in FIG. 1;

FIG. 5 is a bottom plan view of the knife handle shown in FIG. 1;

FIG. 6 is an enlarged front elevational view of the knife handle shown in FIG. 1; and,

FIG. 7 is an enlarged rear elevational view of the knife handle shown in FIG. 1.

The broken lines shown in the drawings are for illustrative purposes only and form no part of the claimed design.
